UNITED STATES PATENT OFFICE.

BENJAMIN FRANK THOMPSON, OF ARLINGTON, MARYLAND.

TELEGRAPH SYSTEM.

1,047,334.

Specification of Letters Patent.

Patented Dec. 17, 1912.

Application filed January 17, 1911. Serial No. 603,065.

To all whom it may concern:

Be it known that I, BENJAMIN FRANK THOMPSON, residing at Arlington, in the county of Baltimore and State of Maryland, 5 have invented certain new and useful Improvements in Telegraph Systems, of which the following is a specification.

This invention relates broadly to means for transmitting intelligence between distant stations, and particularly to an improved system of multiplex telegraphy.

One of the objects of the invention is to provide a new and improved system of quadruplex telegraphy which presents an increased margin of operation over systems of this character as hitherto constructed.

Another object is to provide a system, wherein the use of neutral relays is eliminated.

20 Another object is to provide a system of the above character, wherein the use of currents of different potential are eliminated, the system operating upon alternating or pulsating currents of a single potential.

25 Another object is to provide a system wherein quadruplex telegraphy may be successfully applied to cable transmission.

Other objects will be in part obvious, and in part specifically set forth in the course of 30 the specification.

In the accompanying drawings, wherein I have shown three forms of embodiments of my invention: Figure 1 is a diagrammatic view showing a system wherein the operating instrumentalities are connected in series with a telegraph line; Fig. 2 is a similar view wherein the operating instrumentalities are connected in bridge of the line; and Fig. 3 is a similar view showing a modified 35 form of transmitting apparatus from that shown in the embodiment of Figs. 1 and 2.

Similar reference numerals refer to similar parts throughout the several views of the drawings.

40 Referring now to the drawings, and particularly to the embodiment illustrated in Fig. 1, A and B, respectively denote terminal stations of a telegraph line, said line being indicated at 1. The line is grounded at each of the terminal stations, and included therein in each station is a source of alternating or pulsating current, said sources of current being indicated diagrammatically at 2 and 3, respectively. These 45 sources of alternating current may or may not be synchronized. Leading from the line

1 in station A are branch wires 4 and 5. Wire 4 leads to a sender key, shown herein as an ordinary telegraph strap key 6, which cooperates with the contact 7 to close the operating current. Contact 7 is connected as by means of the wire 8 with one terminal of the rectifier 9. In the present instance, this rectifier is faced to permit the passage of the positive half of the alternating or pulsating current wave. As indicated in the drawings, the opposite terminal of the rectifier 9 is connected as by means of the wire 10 at the central or neutral point 11 of the windings 12 and 13 of the relay 14. Leading from the coil 12 of the relay 14 is a wire 15 which is a continuation of the branch 4 and which connects with the line 1 at 16. Leading from the coil 13 of the relay 14 is a wire 17 which connects at 18 with the wire 19 grounded at 20 through an artificial line 21, said artificial line being common in the art of multiplex telegraphy. Located upon the legs 22 and 23 of the relay 14 are other coils 24 and 25. Coils 12 and 24 and coils 13 and 25 constitute equal and parallel windings on the legs 22 and 23, respectively. Leading from one end of the coil 24 is a wire 26, which connects with the artificial line at 18 and leading from one end of the coil 25 is a wire 27 which is connected with one terminal of the rectifier 28, the opposite terminal being connected with the branch wire 15 at 29. The rectifier 28 is faced to permit of the passage of the negative half waves of the alternating or pulsating current wave flowing over the line from the branch line 15. Relay 14 is provided with the armature 30, which in the present instance is a biased armature, the same normally resting against a stop as indicated at 31. Armature 30 is adapted to close a local circuit 32 by its engagement with the contact 33, such local circuit including a source of current, shown herein as a battery 34, and the usual sounder mechanism 35. The armature 30 is so biased that it will respond only to a current of a given polarity. To compensate for the internal resistance of the rectifier 28, it may be necessary to insert 30 resistance in the wire 15 between the winding of the coil 12 and the point of connection 29, such resistance being omitted from the present drawing in the interest of clearness of illustration. The branch wire 5 extends through strap key 36, wire 37 and rectifier 38, the same being faced to permit the

sending of one or two messages from station B to the station A, when key 6' is actuated the relays 14', 44' and 44 will remain inactive, while the relay 14 is operated. When the message is sent by means of the key 36', the relays 44', 14' and 14 will remain inactive while the relay 44 is operated to work the sounder apparatus. When messages are sent simultaneously by manipulation of keys 6' and 36', the relays 14 and 44 will be operated, while the relays 14' and 44' will remain inactive. Taking now the case of where two messages are sent simultaneously in opposite directions, over the line between stations A and B, the keys 6 and 6' are operated to permit passing of half wave currents of the same polarity and in equal potential on the line. The effect of this will be that one half of the current impressed upon the line from the source in station A will pass through the coil 13 to the artificial line 21, the other half being neutralized by the incoming current from the distant station. The current impressed upon the line by the source of supply in the station B by key 6' will divide, one half passing through the coil 13' to the artificial line 21', the other half being neutralized by the incoming current from station A. Thus the relay 14 will be actuated by the key 6, but said actuation will be in accordance with the particular telegraphic signal impressed upon the line from the key 6'. Likewise, the relay 14' will be actuated by the key 6' in accordance with the particular telegraphic signal impressed upon the line by the key 6. In other words, the operator in each station will work his own relay, but said relay will be operated in accordance with the particular telegraphic signal impressed upon the line by the operator in the distant station. It will be understood that the above conditions will exist only when the keys 6 and 6' are being operated to transmit the same telegraphic signal, and are held in engagement with their contact for an equal period of time. In the absence of these conditions, the manipulation of the keys in each station will of course operate the relay in the distant station in correspondence with that impulse. When all four of the telegraphic sender keys 6 and 6', and 36 and 36' are operated simultaneously four messages will be sent over the wire 1, two in each direction. In this case the rectifier 9 will pass the positive half of the alternating or pulsating current wave, and the rectifier 38 the negative half. The rectifier 9' will take care of the positive half of the alternating or pulsating wave, while the rectifier 38' will take care of the negative half. This will result in the operation of all the relays, in the manner which has just been described in connection with the simultaneous operation of the keys 6 and 6'. In the instance of the operation

of the apparatus indicated at A' and B'' where such apparatus is operated simultaneously, the manipulation of the key 6 will effect the operation of the relay 14', and the manipulation of the key 36' will effect the operation of the relay 44. Likewise when the sender apparatus in stations A'' and B' are simultaneously operated, the relay of the apparatus B'' will be operated by the negative half waves impressed upon the line by the key 36 and the relay of the apparatus A' will be operated by the positive half waves impressed upon the line by the key 6'.
72

Referring now to the embodiment of my invention shown in Fig. 2, I have illustrated therein a system wherein the telegraphic receiving apparatus is connected in bridge of the line. In this embodiment of my invention, as in the first described embodiment, the line 1 is grounded at both ends, and a source of alternating or pulsating current indicated at 2 and 3 is connected in the line at each end. These sources of alternating current supply may or may not be synchronized, but it is desirable that both shall supply currents of substantially equal potential. In this embodiment I have also indicated two terminal stations at A and B, respectively with two sets of apparatus A' and A'' and B' and B'' in each station. Leading from one end of the line 1 are branch wires 60 and 61, the former of which is connected with the telegraphic sender key 62, which co-operates with the contact 63, to close the circuit. Leading from contact 63 is a wire 64 connected with the terminal of the rectifier 65, so faced as to permit the passage of the negative half of the alternating or pulsating current wave impressed upon the line by the key 62. Connected with the opposite terminal of the rectifier 65 is a wire 66 which leads to the connection 67' of the line 1. The wire 61 leads to the telegraph key 67 which co-operates with contact 68 to close the circuit and connected with the contact 68 is a wire 69 which, in turn, is connected with one terminal of the rectifier 70, so faced as to permit the passage of the positive half of the alternating or pulsating current there-over. The opposite terminal of the rectifier 70 is connected by wire 71 with the point of contact 67' and with the line 1. The line 1 leads from the point 67' to two arms 72 and 73 of the bridge. Suitable resistances as at 74 and 75 are provided in arms 72 and 73, respectively, said resistances being interposed to keep the balance between the respective arms of the bridge. Arm 72 leads through resistance 74 to similar resistances 74' in the opposite end of the line, thence to the point of jointure of the arms 72' and 73' of the bridge at 77 at the opposite terminal station, indicated herein at B. The line in station B is provided with branches 71' and 66', the former of which is connected with 130

one terminal of the rectifier 70' from the opposite terminal of which leads a wire 69' to the contact 68', with which co-operates the telegraphic key 67'. This key is connected 5 with the branch wire 61' which leads to the point of connection 78. From this point the line leads through the wire 79 to the source of alternating current 3, to ground. The leg 73 of the bridge is connected through 10 resistance 75, thence by wire 81 to artificial line 80, to ground, and the arm 75' is connected with resistance 75', thence by wire 81' to artificial line 80', to ground. The relays 82 and 83 of the receiving apparatus A' and 15 A'' are connected in an independent bridge between the line 1 and artificial line 80. The bridge 84 of the relay 82 is provided with a rectifier 85, so faced as to permit the passage of the negative half of the alternating or pulsating current wave, and the bridge 86 of the relay 83 is provided with a rectifier 87 so faced as to permit the passage of the positive half of the alternating or pulsating current wave. The relays 82 and 20 83 are indicated herein diagrammatically as of the polar type, although neutral relays may be employed if desired, and the armatures 88 and 89 in the present instance are intended to be biased and held in engagement with contacts 90 and 91 respectively. Armature 89 is connected in a local circuit 92 and is adapted to close such circuit by engagement with the contact 93, such local circuit including the source of current supply 94, and the telegraphic sounder apparatus 95. I also contemplate the substitution for the relays 82 and 83, respectively, of telephone receivers, which might be employed as receiving apparatus. The armature 89 of the relay 86 is adapted to close the local circuit 96 which includes the source of supply 97, and the telegraphic sounder apparatus 98. The relays 82' and 83' of the apparatus B' and B'' in station B and 25 the auxiliary apparatus are the same in all respects to those in station A just hereinbefore described, and therefore the construction and operation are believed to be clear without further explanation. The manner in which this embodiment of my invention operates may now be understood. Taking in the case for instance when it is desired to send a single message from station A to station B, when key 67 is 30 manipulated and caused to engage the contact 68, the circuit being thus closed, the positive half wave passes through wire 69, the negative half having been separated out by the rectifier 70. The current then passes 35 from the rectifier 70 through the wire 71 to the line 1, whence one part of such current flows over the arm 72 of the bridge, the other part passing through the arm 73, resistance 75, wire 81 to the artificial line 40 to ground. The part of the current passing through the arm 72 of the bridge then passes 45 through resistance 74 to the line 1, the potential being the same at the station A as between the main line 1 and the artificial line 80, the relays 82 and 83 are inactive. The portion of current passing over line 1 to station B is precluded from passing through the relay 82' by reason of the facing of the rectifier 85' in the bridge 84'. This part of the current then passes through the rectifier 87', and operates the relay 83' passing 50 through the wire 81 and artificial line 80' to ground. The effect of the operation of the key 67 at station A is similar to that of the key 67', save that the negative half of the alternating or pulsating current wave passes over the line 1 and operates the relay 82' of the bridge 84', whence if passes through the artificial line to ground. The same results would obtain if it is desired to transmit single messages from either of the sending apparatus in station B to the corresponding receiving apparatus in station A. From the above it should also be clear that the simultaneous operation of the sending apparatus at either of the stations A or B will result in two messages being transmitted over the line without interference and being received by the receiving apparatus in the distant station. When for instance the sending keys 62 in station A and the sending key 62' in the station B are operated simultaneously to transmit two signals between stations A and B. The current half wave divides at the point 77, one portion passing through the wire 73', resistance 75', wire 81', thence through the artificial line 80' to ground, the other portion passes through resistance 74', line 1, bridge 84' including the rectifier 85', which is faced to pass the negative half of 60 the alternating current. The current then passes through relay 82', thence through wire 81', and the artificial line 80' to ground. The operation of the corresponding apparatus at station A is similar to that just 65 above described, the negative half of the alternating or pulsating current wave operating the receiving device 82. This condition of course is only existent when the keys 62 and 62' are engaged with their respective 70 contacts for an equal period of time, for when the period of such engagement is unequal then the sounding apparatus at each station operates the corresponding receiving apparatus at the distant station. When the 75 keys 62 and 67 in station A and the keys 62 and 67' are simultaneously operated four messages will be transmitted simultaneously over the line 1, two in the same direction without interference. The relays are operated in a manner identical to that which has been just above described. Referring now to the embodiment of my invention illustrated in Fig. 3, the receiving apparatus in stations A and B are identical 80

- to those of stations A and B in the embodiment shown in Fig. 2. In this case, however, I have provided a modified form of transmitting apparatus in each of stations A and B, the same being the well known form of "walking beam" transmitting apparatus. The transmitter 99 is actuated by means of the magnet 100 upon which is located a coil 101 of the local circuit 102, which includes a suitable source of current supply as battery 103, such apparatus being adapted to be closed by telegraph strap key 104. The transmitter 99 normally rests in engagement with the contact 105 from which leads wire 106. Wire 106 is grounded through a resistance 107, such resistance being equal to the resistance of the source of current. The object of this construction is to improve the balance of the line. In other words, under this arrangement of the system, a better transmission of signals would obtain owing to the fact that a greater portion of the operating current would flow through the receiving apparatus at the respective terminals, and less through the artificial line to ground. The operation of this embodiment in so far as the transmission of messages is concerned is identical to that as illustrated in Fig. 2 of the drawings.
- As many changes could be made in the above construction and many apparently widely different embodiments of this invention could be made without departing from the scope thereof, it is intended that all matter contained in the above description or shown in the accompanying drawings shall be interpreted as illustrative and not in a limiting sense. It is also to be understood that the language used in the following claims is intended to cover all of the generic and specific features of the invention herein described and all statements of the scope of the invention, which as a matter of language might be said to fall therebetween.
- Having thus described my invention, what I claim as new and desire to secure by Letters Patent, is:
1. In a system of the class described, the combination with a line, of a source of alternating current supply connected thereto at each terminal, two independent sets of transmitting and receiving instruments connected in the line at each station, means combined with each set of transmitting and receiving instruments for discharging therethrough current waves of a single polarity, a plurality of coils, each of which comprises a plurality of windings, rectifying means associated with one of the windings of each coil, there being a set of coils and associated rectifying means for each receiving instrument, said coils and associated rectifying means being adapted, when a transmitting instrument at one station is operated, to render both sets of receiving instruments at that station, and one receiving instrument at the distant station, neutral to the transmitting instrument operated.
  2. In a system of the class described, the combination with a line, of a source of alternating current supply connected thereto at each terminal, two sets of transmitting and receiving instruments connected in multiple series in the line at each terminal, means combined with each set of transmitting and receiving instruments for discharging therethrough current waves of a single polarity, a plurality of coils, each of which comprises a plurality of windings, an artificial line connected with one of said windings, rectifying means associated with one of the windings of each coil, there being a set of coils and associated rectifying means for each receiving instrument, said coils and associated rectifying means being adapted, when a transmitting instrument at one station is operated, to render both sets of receiving instruments at that station, and one receiving instrument at the distant station, neutral to the transmitting instrument operated.
  3. In a system of the class described, the combination with a line, of a source of alternating current supply connected thereto at each terminal, two sets of transmitting and receiving instruments connected in the line at each terminal, means for causing current pulsations of opposite signs to flow through said sets of transmitting and receiving instruments at each terminal, a plurality of coils, each of which comprises a plurality of windings, rectifying means associated with one of the windings of each coil, there being a set of coils and associated rectifying means for each receiving instrument, said coils and associated rectifying means being adapted, when one transmitting instrument is operated, to render the receiving instrument associated with the transmitting instrument operated, and two other receiving instruments, neutral to said transmitting instrument operated.
  4. In a system of the class described, the combination with a line, of a source of alternating current supply connected thereto at each terminal, transmitting and receiving apparatus including a relay connected with the line at each terminal, means combined with each set of transmitting and receiving apparatus for discharging therethrough current waves of a single polarity, said relay having positioned thereon a plurality of coils, each of which comprises a plurality of windings, and rectifying means associated with one of the windings of each coil, there being a set of coils and associated rectifying means for each receiving instrument.
  5. In a system of the class described, the combination with a line, of a source of alter-

nating current supply connected thereto at each terminal, transmitting and receiving instruments connected with a line at each terminal, means combined with each set of transmitting and receiving instruments for discharging therethrough current waves of a single polarity, a plurality of coils, each of which comprises a pair of independent windings, rectifying means associated with 10 one of the windings of said coils, there being a set of coils and associated rectifying means for each receiving instrument, said coils and associated rectifying means being adapted when a transmitting instrument at

one station is operated, to neutralize both 15 receiving instruments at one terminal and one of the receiving instruments at the distant terminal, when either of the transmitting instruments at the first named terminal is operated.
